(57) **CLAIM**

I claim the ornamental design for a nail for bone fracture fixation, as shown and described.

DESCRIPTION

FIG. 1 is a perspective view of the nail for bone fracture fixation showing my new design;

FIG. 2 is a left side view thereof;

FIG. 3 is a right side view thereof;

FIG. 4 is a front side view thereof;

FIG. 5 is a back plan view thereof;

FIG. 6 is a bottom plan view thereof;

FIG. 7 is a top plan view thereof;

FIG. 8 is a cross-sectional view thereof; and,

FIG. 9 is an exploded view thereof.

The broken lines in the drawings illustrate unclaimed environment only and form no part of the claimed design.

1 Claim, 6 Drawing Sheets
